(74) *Attorney, Agent, or Firm*—Gifford, Krass, Groh Sprinkle, Anderson & Citkowski, P.C.

(57) **CLAIM**

The ornamental design for a light up toy rocket, as shown and described.

DESCRIPTION

FIG. 1 is a perspective view of the toy rocket according to the present design;

FIG. 2 is a partially exploded perspective view of the present design;

FIG. 3 is a right side elevational view of the partially exploded design of FIG. 2 illustrating the projectile portion in a first rotational position;

FIG. 4 is a succeeding side elevational view illustrating the projectile in a further rotated position;

FIG. 5 is a left side elevational view of the partially exploded design of FIG. 2 illustrating the projectile in a further rotational position;

FIG. 6 is a succeeding side elevational view illustrating the projectile in a still further rotational position;

FIG. 7 is a front elevational view of the partially exploded illustration of FIG. 2; and,

FIG. 8 is a corresponding rear elevational view of FIG. 2.
